UNITED STATES PATENT OFFICE.

GEORGE A. JONES, OF PALMETTO, FLORIDA.

DESIGN FOR A TOOL-CHEST.

57,436.

Specification for Design. Patented Mar. 29, 1921.

Application filed December 27, 1919. Serial No. 347,859. Term of patent 14 years.

To all whom it may concern:

Be it known that I, GEORGE A. JONES, a citizen of the United States, residing at Palmetto, in the county of Manatee and State of Florida, have invented a new, original, and ornamental Design for a Tool-Chest, of which the following is a specification, reference being had to the accompanying drawing, forming part thereof.

Figure 1 is a perspective view.

Fig. 2 is an end elevation of the tool chest showing my new design.

I claim,

The ornamental design for a tool chest as shown.

GEORGE A. JONES.
